STOVE CONSTRUCTION

Herbert M. Reeves, Kankakee, Ill., assignor to
 Florence Stove Company, Gardner, Mass., a
 corporation of Massachusetts

Application May 19, 1950, Serial No. 163,048

5 Claims. (Cl. 126—1)

1

The invention relates to improvements in the construction of gas or like cookstoves and more particularly to cookstoves of the type in which the stove body is made up of a plurality of enameled sheet metal panels carried by a rigid chassis or frame.

One object of the invention is to provide a construction which materially reduces the time and labor required for assembling the stove body.

Another object is to provide a stove construction in which the various panels of the stove body are designed for assembly with the frame in a predetermined sequence and in which the later assembled panels effectively lock previously assembled panels in place on the frame.

A more specific object is to provide a stove construction in which the various panels are attachable to the frame by cooperating fastening elements engageable simply by shifting the panels edgewise relative to the frame, thus eliminating the need for bolts or screws to maintain the parts in assembled relation.

Still another object is to provide fastening means for attaching panels to a stove frame which is simple in construction, quick and easy acting and which is capable of holding the parts securely in place after assembly.

Other objects and advantages of the invention will become apparent from the following detailed description of the preferred embodiment illustrated in the accompanying drawings, in which:

Figure 1 is a perspective view of a stove frame and panel assembly embodying the features of the invention;

Fig. 2 is an exploded front view of the frame and panel assembly constituting the stove body;

Fig. 3 is a perspective of one of the end panels as viewed from its inner side;

Fig. 4 is a fragmentary side view of the lower part of the stove body showing the interlocking engagement between an end panel and the base portion of the frame;

Fig. 5 is a sectional view taken in the vertical plane substantially on the line 5—5 of Fig. 4;

Fig. 6 is a sectional view through the top and one end panel of the stove taken in a vertical plane substantially on the line 6—6 of Fig. 1;

Fig. 7 is a fragmentary perspective view, partly in section, showing details of a part of the fastening means for attaching the top and end panels to the stove frame.

Fig. 8 is a fragmentary sectional view through the top and front frame member of the stove body taken in a vertical plane substantially on the line 8—8 of Fig. 1;

2

Fig. 9 is a sectional view taken in a horizontal plane substantially on the line 9—9 of Fig. 8;

Fig. 10 is a fragmentary sectional view through the rear portion of the top panel and the stove frame taken in a plane substantially on the line 10—10 of Fig. 1;

Fig. 11 is a sectional view taken in offset planes substantially on the line 11—11 of Fig. 10; and

Fig. 12 is a sectional view taken in a horizontal plane substantially on the line 12—12 of Fig. 11.

While the invention is susceptible of various modifications and alternative constructions and uses, I have shown in the drawing and will herein describe in detail one embodiment of the invention. It is to be understood, however, that I do not intend to limit the invention by such disclosure, but aim to cover all modifications and alternative constructions and uses falling within the spirit and scope of the invention as expressed in the appended claims.

For purposes of illustration, the invention has been shown as applied to the construction of a stove body 15 for a table top gas cookstove. As herein shown, the body 15 comprises a rigid, generally rectangular frame 16 closed at opposite ends by end panels 17 and at the top by a top panel 18. An upright back guard panel 19 extends along the rear edge of the stove top. The panels 17, 18 and 19 which are commonly made of sheet metal such as steel, and other exposed parts of the stove, are usually finished with a coating of vitreous enamel.

In the exemplary stove, the frame 16 is constructed of sheet metal stampings welded or otherwise permanently secured together to form a light weight, rugged structure. In general the frame comprises a front frame member 20 (Figs. 1 and 2) extending the full width of the stove and a similarly dimensioned rear member 21 (Fig. 10) connected at opposite ends adjacent their upper edges by end members 22 (Figs. 6—8 and 10) and adjacent their lower edges by end members 23 (Figs. 1, 4 and 5). The latter end members, together with a front member 24 (Figs. 1 and 2) and a rear member (not shown) constitute the base of the stove body.

In accordance with the invention, the end, top and back guard panels 17, 18 and 19 and the frame 16, are constructed and arranged so that the panels may be attached to the frame by a simple edgewise sliding movement. Moreover, the construction provides for assembly of the panels with the frame in a predetermined sequence with the panels so related to each other that each of them except the last is positively locked in place on the frame. More specifically stated, the ar-

arrangement is such that the end panels 17 which are first assembled with the frame by an edge-wise movement, as above stated, are positively locked in place upon assembly of the top panel 18 with the frame. The top panel 18, in turn, is positively locked in place by assembly of the back guard panel 19 with the frame.

To provide for assembly of the panels with the frame in the above manner, cooperating fastening means are provided thereon. Such fastening means may be of any preferred construction embodying elements adapted to be engaged by relative movement of one element relative to the other. In the exemplary stove body, the frame is provided at each end with fastening elements 26 (Figs. 6 and 7) and 27 (Figs. 10-12), which serve additionally as supporting and guiding means for the panels, as will appear presently. In the present instance the elements 26 are located adjacent the front of the frame, one at each side, and the elements 27 are located at the rear of the frame.

As herein shown, the fastening elements 26 which are alike, each comprises an L-shaped bracket having one leg disposed horizontally and secured to the top of the frame 16 as by stove bolts 28. The other leg of the bracket extends upwardly substantially in alignment with the end of the frame and its end portion is slotted to provide upstanding parallel fingers 29 and 30. The finger 29 is somewhat shorter than the companion finger and its intermediate portion is bent so as to offset the free end of the finger outwardly, as shown in Figs. 6 and 7.

As will be seen by reference to Fig. 10, each of the fastening elements 27 comprises an angular sheet metal stamping having its lower end portion 31 (Figs. 10 and 11) secured to the upper end of one of the diagonal braces 25 as by stove bolts 32. An intermediate portion or web 33 extends generally upwardly and rearwardly from the end 31 and terminates in an upright upper end portion 34. In the illustrative embodiment, a section 35 of the web 33 is bent over at an angle so as to locate the upper end 34 of the element and the adjacent portion of the web 33 in inwardly offset relation to the lower end 31 of the element (see Fig. 11).

The forwardly facing edge of the web 33 is formed with a series of fingers or extensions, three in the present instance, for cooperation with the end and top panels of the stove body. One extension 36 is located adjacent the lower end 31 of the element and is extended vertically upwardly in the same plane as the end, to serve as a support and guide for the end panel 17. The other two extensions, 36 and 37, are formed on the upper or offset part of the web 33 and extend generally forwardly. As shown in Fig. 10, the extensions 36 and 37 are separated by an arcuate slot 38 adapted to receive a part of the top panel 18 and thus enable the extensions to restrain the top panel against up or down movement, as will be described presently.

Additional fastening means for the end panel 17 include hook elements herein shown as forwardly bent lugs 40 (Figs. 8 and 9) on the outwardly turned flanges 41 provided at opposite ends of the front frame member 20. As shown in Figs. 4 and 5, each of the base members 23 is provided with a pair of spaced upwardly opening pockets 42 formed by striking in a section of the member so as to define a horizontal ledge or abutment 43. The portion of the member between the pockets 42 is slotted and then turned outwardly as at 44 to afford access to the pockets.

Referring now to Figs. 3-8, the end panels 17 are alike except that they are reversely shaped for the right and left-hand ends of the stove body. Each panel has an inwardly turned flange 45 extending entirely around its peripheral edge. The marginal edge portion 46 of the flange along the upper edge of the panel is turned downwardly and adapted to hook over the upstanding finger 29 of the fastening element 26 and over the extension 39 of the fastening element 27. Likewise, the marginal edge portion 47 of the front flange 45 is turned rearwardly for hooking over the lugs 40 on the front frame member 20, as shown in Figs. 8 and 9. The bottom flange 45 of the panel 15 has the central portion of its marginal edge turned downwardly to form an elongated tongue 48 adapted to fit into the pockets 42 as shown in Figs. 4 and 5. With this arrangement each end panel 17 may be attached to the stove frame 16 by simply locating it closely adjacent the end of the frame and then shifting it edgewise downwardly to inter-engage the fastening elements above described.

The top panel 18 is generally rectangular in form and is provided with suitable openings for the burner boxes in which the stove burners are located in the fully assembled stove. The particular stove illustrated is of the so-called divided top type having a burner box at each end and accordingly two similarly spaced openings 50 are provided in the top panel, as shown in Fig. 1. In practice the burner boxes are formed with a bottom wall 51 (Fig. 8) in the form of a metal plate welded or otherwise rigidly attached 30 to the top of the stove body 16. In the present instance the walls 51 are extended forwardly of the frame to form overhanging shoulders 52 for locking engagement with the top panel 18, as will be described presently.

At its front edge the top panel 18 is formed with a relatively wide depending flange 53 and at the side edges with depending flanges 54 which at the front are of the same width as the flange 53, but which are substantially narrower throughout the major portion of their length. The front flange 53 serves as a closure for the burner boxes and intermediate portion of the stove and is suitably apertured to provide clearance for the burner valves and other controls. At its rear edge the panel 18 is formed to provide a flat base 55 (Fig. 10) spaced upwardly from the plane of the panel for cooperation with the back guard panel 19. The front wall 56 of this base portion merges with the body of the panel in a gently rounded curve, as will be seen in Figs. 1 and 10.

In the preferred form of the stove body illustrated, the side flanges 54 of the top panel are shaped for cooperation with the fastening elements 26 and 27 heretofore described and to define abutments effective to restrain the end panels 17 against movement either forwardly or upwardly. For this purpose the wide and narrow sections of the flange 54 are joined by an upwardly sweeping curved portion 57 which serves as an abutment for the complementally shaped upper end of the panel 17. The lower or free edge portion 58 of each of the flanges 54 is turned inwardly and when assembled with the other parts of the stove body, is adapted to cooperate with bosses 59 struck up from the top flange 45 of the adjacent side panel 17, as shown in Figs. 6, 7, 10 and 11.

For cooperation with the fastening elements 75 26 the flange portion 58 at each side of the top

panel is formed adjacent the front edge of the panel with a depending tongue 60 (Figs. 6 and 7) adapted to be entered between the flange 46 of the end panel 17 and the upright finger 30 of the associated fastening element 26. Adjacent the rear of the top panel each of the flange portions 58 is formed with a second depending tongue 61 (Figs. 10 and 11) adapted to bear against the web 33 of the fastening element 27. The tongues and fastening elements are thus effective to accurately locate the top panel with respect to the stove frame and to restrain it against lateral movements relative to the frame.

To secure the top panel 18 against vertical movements relative to the frame, the flange portions 58 are formed adjacent the rear of the panel with inwardly projecting lugs 62 (Figs. 10-12) adapted to be inserted between the extensions 36 and 37 of the fastening elements 27. Engagement of the lugs between the extensions is effected by placing the top panel upon the stove frame with the lugs 62 at the mouth of the slot 38 and then shifting the panel rearwardly. Such rearward movement is also utilized to secure the front end of the panel to the stove frame by entering the inturned edge portion 63 (Fig. 8) of the front flange 53 below the shoulder 52 defined between bottom walls 51 of the burner box.

The rearward or fastening movement of the top panel 18 above described, brings the curved section 57 of the flange 58 into engagement with the complementally shaped flanges of the end panels 17, thus effectively locking the end panels against forward movement. As the flange portions 58 of the top panel overlie the top flanges 45 of the end panels, the latter are also positively locked against upward disengaging movements. Thus the later assembled top panel 18 serves to positively lock both of the previously assembled end panels 17 to the stove frame.

The back guard panel 19 may be of any preferred construction, the present invention being concerned primarily with its mounting on the stove frame. As shown in Figs. 1 and 2, the guard panel comprises a sheet metal stamping having a generally upright front face 65 with a rearwardly turned flange 66 extending around its top and side edges. The lower end of the panel stamping is shaped and dimensioned to fit tightly against the base 55 provided for it on the top panel 18.

For attaching the back guard panel 19 to the stove frame, two mounting brackets are rigidly secured within the panel structure, each presenting a downwardly directed fastening element or prong 67 (Figs. 2 and 10-12). The prongs 67 are aligned with openings 68 in the base wall 55 of the top panel, which openings are disposed directly above the end portions 34 of the fastening elements 27. Those end portions 34 have their side edges 69 bent inwardly to form channel-like guides or sockets for the reception of the prongs 67. Preferably the sockets are dimensioned for a snug fit with the prongs whereby the top panel is held securely in place. The lower ends of the prongs may be bent inwardly as shown in Fig. 11, to facilitate their engagement in the sockets.

With the above arrangement the back guard panel 19 may be attached to the stove frame 16 by simply inserting the prongs 67 through the opening 68 in the top panel and then shifting the guard panel downwardly to engage the prongs 67 in the sockets formed by the elements 34. The frictional engagement of the prongs

and sockets is sufficient to hold the guard panel securely in place. It will be apparent that the insertion of the prong 67 through the opening 68 of the top panel will effectively lock the top panel against a forward disengaging movement, thereby securely locking the panel in assembled relation with the stove frame.

It will be apparent from the foregoing that the invention provides a stove body of novel and advantageous construction which can be assembled very quickly and with a minimum of labor. The end panels 17 may be attached to the stove frame 16 by simply placing them against the ends of the frame and then shifting them edgewise in a downward direction. This engages the upper flanges 46 of the panels over the fastening element fingers 29 and over the extensions 39. It also engages the front flanges 47 over the lugs 40 and enters the tongues 48 in the pockets 42. Top panel 18 is then attached by initially placing the panel so that the lugs 62 line up with the notches 38 in the fastening elements 27 and then shifting the panel edgewise rearwardly of the stove frame. The lugs 62 are thus wedged between the extensions 36 and 37 and the front flange 63 is engaged under the shoulder 52 at the front of the frame. When so assembled the side flanges 58 of the top panel bear against the top flanges 45 of the end panel 17 and positively lock them against an upward disengaging movement. Moreover, the rounded shoulder portions 57 of the flange 58 abut against the complementally shaped shoulders on the end panels and effectively restrain them against forward movement. The final step of the assembly, namely, the installation of the back guard panel 19, is effected by inserting the prongs 67 through the opening 68 in the top panel and forcing the guard panel downwardly to engage the prongs in the channel-like sockets 69. The prongs thus thus hold the guard panel securely in place and additionally positively lock the top panel against a forward disengaging movement. Thus a rigid and permanent assembly of the body is effected very quickly and without requiring the use of bolts, screws or similar fasteners.

The fastening means discerned in the present instance present definite advantages from the standpoint of low cost and ease of assembly and represent the preferred form. It will be appreciated, however, that any other suitable fastening means may be utilized which permit assembly of the panels in the novel cooperative relationship above described so that the later installed panels are operative to positively lock previously installed panels in place as the stove frame.

I claim as my invention:

1. A stove body comprising, in combination, a generally rectangular frame, a top panel closing the top of said frame, means for attaching the top panel to the frame including cooperating fastening elements on the panel and frame engageable by a rearward movement of the top panel relative to the frame and effective when engaged to restrict the panel solely to forward movement, a back guard panel extending along the rear edge of said top panel, and means for attaching said back guard panel to the frame including prong elements on the panel and cooperating socket elements on said frame engageable by a downward movement of the panel relative to the frame, said top panel having a portion underlying said back guard panel formed with apertures through which the prong elements on

the back guard project to prevent a forward disengaging movement of said top panel.

2. A stove body comprising, in combination, a generally rectangular frame, side panels removably mounted on the frame, a top panel closing the top of said frame and operative to lock said side panels to the frame, means for attaching the top panel to the frame including cooperating fastening elements on the top panel and frame engageable by a rearward movement of the top panel relative to the frame, a back guard panel extending along the rear edge of said top panel, and means for attaching said back guard panel to the frame including cooperating prong and socket elements on the back guard panel and frame respectively engageable by a downward movement of the back guard panel relative to the frame, said top panel having a portion underlying said back guard panel and extending over the socket elements on the frame, said underlying portion of the top panel having openings aligned with the socket elements for the passage of the prong elements on the back guard panel whereby the latter elements are enabled to effectively lock the top panel in assembled relation with the frame.

3. A stove body comprising, in combination, a generally rectangular frame comprising front and rear frame members, upper and lower cross members connecting said front and rear frame members at opposite ends, closure means for opposite ends of said frame, each of said closure means comprising a sheet metal panel having an inwardly and reversely turned flange extending along its front and top edges and an inwardly turned flange terminating in a downwardly directed tongue extending along its lower edge, hook elements formed on said front frame members for cooperation with the reversely turned portions of the front flanges of the panels, upwardly opening pockets formed in the lower cross members of the frame for the reception of the tongues on said panels, and fastening elements mounted adjacent the ends of said frame for cooperation with the reversely turned portion of the top flanges of the panels, said flanges being engageable with said hook elements and said fastening elements and said tongues being engageable in said pockets by downward sliding movements of the panels relative to the frame.

4. A stove body comprising, in combination, a generally rectangular frame, end panels adapted to close opposite ends of the frame, fastening means including upper and lower elements on each panel and complemental upper and lower elements on said frame engageable by downward movements of the panels relative to the frame securing the panels to the frame and acting when engaged to restrict them solely to upward movement, a top panel adapted to fit over the top of

said frame, fastening means at opposite sides of said frame each including a member defining upstanding fingers spaced apart to receive a fore-and-aft flange depending from the top panel to guide the same for movement relative to the frame in a front to rear direction, a back guard panel adapted to extend along the upper rear edge of said frame, and fastening means including depending prongs adjacent opposite ends of said back guard panel and complemental socket elements on said frame engageable by a downward movement of the back guard panel relative to the frame, said prongs when engaged in said sockets coacting with said top panel to block the same against movement either forwardly or rearwardly and thereby positively lock the top and end panels in assembled relation with the frame.

5. A stove body comprising, in combination, a generally rectangular frame, end panels for opposite ends of the frame, fastening means including upper and lower elements on the end panels and complemental upper and lower elements on the frame engageable by downward movements of the end panels relative to the frame to secure said end panels to the frame, a top panel for said frame, fastening means including elements adjacent opposite ends of said top panel and complemental elements on said frame engageable by a rearward edgewise movement of the top panel relative to the frame to secure the top panel to the frame, said top panel defining abutments cooperative with complemental abutments on the end panels to restrain said end panels against upward disengaging movements, a back guard panel adapted to extend along the upper rear edge of said frame, and fastening means including prongs on said back guard panel and complemental socket elements on said frame engageable by a downward movement of the back guard panel relative to the frame, the prongs on said back guard panel when engaged in the sockets on the frame cooperating with said top panel to restrain it against a forward disengaging movement.
